UNITED STATES PATENT OFFICE.

AMABLE OLIVER PATENAUME, OF TORONTO, ONTARIO, CANADA, ASSIGNOR OF ONE-HALF TO ORVILLE BENJAMIN SHORTLEY, OF TORONTO, ONTARIO, CANADA.

SPLIT STOVEPIPE.

Application filed May 5, 1927. Serial No. 189,015.

My invention relates to improvements in split stove pipes, and the object of the invention is to devise a pipe section of this type in which the split edges of the section will be locked together with a maximum rigidity, and which at the same time can be engaged and disengaged in a minimum amount of time and with a maximum amount of ease, and it consists essentially of the arrangement and construction of parts as hereinafter more particularly explained.

Fig. 1 is a side elevation of a stove pipe section constructed in accordance with my invention and showing the split edges of the section detached and slightly separated apart.

Fig. 2 is a similar view to Figure 1 showing the split edges in the engaged position.

Fig. 3 is an enlarged sectional detail of one of the locking connections in the engaged position.

Fig. 4 is a similar view to Figure 3 showing the members of the lock in the partially engaged position.

In the drawing like characters of reference indicate corresponding parts in each figure.

1 indicates a stove pipe section provided with edge portions 2 and 3 forming the sides of the split opening of the section. 4 are a series of inverted T-shaped slots arranged in a series parallel with the edge of the split portion 2 and spaced an equal distance apart. The T-slots 4 form opposing tongues 4^x and 4° at each side of the slot.

5 and 6 are inverted L-shaped slots located in the split edge portion 3, the L-slots opposing one another and forming an intervening strip 5^x between the horizontal arms 40 of the L and forming opposing tongues 6^x and 6° forming enlargements to the strip 5^x and located beneath the vertical arms of the inverted L-shaped slots.

It will be noted on referring particularly to Figure 1 that the vertical arms of the inverted T-slots 4 are graduated in length decreasing from the top of the section towards the bottom.

The tongues 6^x and 6° of the slots 5 and 6 50 are correspondingly graduated.

When it is desired to interlock the opposing edges 2 and 3 of the split pipe together all it is necessary to do is to overlap

the edge 2 over the edge 3 bringing the vertical arm of each T-slot 4 in vertical alignment with each of the strips 5^x intervening between the slots 5 and 6.

When this is done the edge portions 2 and 3 are moved longitudinally of the stove pipe section in opposite directions thereby carrying the tongue portions 4^x and 4° into engagement with the tongue portions 6^x and 6° or in the position shown in Figure 4. By further moving the edge portions 2 and 3 longitudinally, the parts are carried to the position shown in Figure 3, the base of the recess formed by the vertical arm of the T-slot 4 extending across the base of the strip 5^x so as to lock against the upper edges of the tongues 6^x and 6°, the base of the tongues 6^x and 6° engaging with the base of the tongues 4^x and 4° as clearly shown in Figure 3.

As the uppermost tongues 4^x and 4° are engaged with the uppermost tongues 6^x and 6° the corresponding tongues of the next pair of slots 4, 5 and 6 are brought into the engaged position, and after these tongues have been engaged the corresponding tongues of the lowermost slots are brought into the engaged position so that each set of tongues of the series of slots are brought successively into the engaged position, thereby enabling of the locking of the section to be performed with a maximum amount of ease.

If desired the tongues 4^x and 4° may be slightly bent inward and the tongues 6^x and 6° slightly bent outward so as to permit of the easy engagement of these tongues. Also the corner of the tongue may be slightly chamfered off for the same purpose.

What I claim as my invention is:—

A split stove pipe section having inverted T-slots adjacent one split edge of the section, a pair of opposing inverted L-shaped slots adjacent the other edge of the section to form an intervening strip portion, and tongues forming enlargements of such strip portion adapted to pass through the horizontal slot of the opposing T-slot when superimposed thereover to pass over the tongue portions formed by the intersecting vertical and horizontal arm portions of the T.

AMABLE OLIVER PATENAUME.
